UNITED STATES PATENT OFFICE.

ROBERT L. GARDNER, OF ST. LOUIS, MISSOURI.

DESIGN FOR A PHOTOGRAPH-HOLDER.

57,188.

Specification for Design.

Patented Mar. 1, 1921.

Application filed May 20, 1918. Serial No. 235,740. Term of patent 14 years.

To all whom it may concern:

Be it known that I, ROBERT L. GARDNER, a citizen of the United States, residing at St. Louis, Missouri, have invented a new, original, and ornamental Design for a Photograph-Holder, of which the following is a specification, reference being had to the accompanying drawing, forming part thereof.

The figure is a front elevational view of a photograph holder showing my new design.

I claim:

The ornamental design for a photograph holder, as shown.

ROBERT L. GARDNER.
